UNITED STATES PATENT OFFICE.

JOHN S. TAYLOR, OF WAIPAHU, TERRITORY OF HAWAII.

FLUSHING APPARATUS.

1,131,570.

Specification of Letters Patent.

Patented Mar. 9, 1915.

Application filed July 22, 1914. Serial No. 852,510.

To all whom it may concern:

Be it known that I, JOHN S. TAYLOR, a citizen of the United States, residing at Waipahu, in Hawaii, have invented new and 5 useful Improvements in Flushing Apparatus, of which the following is a specification.

This invention relates to flushing apparatus, the object of the invention being to provide automatic flushing apparatus which is 10 thrown into operation by the weight of a person standing on a depressible platform and which is automatically thrown out of operation as soon as said person steps from the platform.

15 A further object of the invention is to provide a special relative arrangement of depressible platform, casing, cut off valve, and connections, whereby immediate and ready access may be had to the valve and said operating connections.

20 With the above and other objects in view, the invention consists in the novel construction, combination and arrangement of parts, as will be hereinafter more fully described, 25 illustrated and claimed.

In the accompanying drawings:—Figure 1 is a vertical sectional view of the flushing apparatus of this invention. Fig. 2 is a horizontal section on the line 2—2 of Fig. 1. 30 Fig. 3 is a vertical section showing the position of the parts when the platform is depressed. Fig. 4 is a detail vertical section through the draining connection of the platform.

35 Referring to the drawings 1 designates the bowl to be flushed, 2 the drain pipe therefrom and 3 the water supply pipe which is arranged to discharge into the bowl, said supply pipe 3 extending under the floor 40 which is shown at 4, the same resting on the floor beams or joists 5.

In carrying out the present invention I provide a depressible platform 6 the upper surface of which is preferably concaved as 45 shown at 7 and provided with a central drain connection or nipple 8 protected at its upper end by a strainer 9, the nipple or connection 8 being telescopically slideable into a drain pipe 10 arranged directly under the 50 platform and leading off to a waste pipe or sewer.

11 designates a casing in which the platform 6 is guided in its vertical movements.

The casing 11 is closed by a bottom wall 12 55 which has only a single opening 13 therein

the purpose of which will appear. The casing 11 is provided along its top edge with a marginal flange 14 which is preferably rabbeted in the floor 4 as shown at 15 so that the upper side of said casing will be 60 flush with the top of the floor.

Within the casing 11 is arranged a valve operating lever 16 which is fulcrumed at 17 on a post 18, the opposite end of said lever resting upon the rounded upper extremity 65 of the stem 19 of a cut off valve 20 which operates in a valve casing 21 incorporated in the water supply pipe 3 as clearly shown in Figs. 1 and 3, the casing 21 being also provided with a threaded plug 22 to enable the 70 valve 20 and its stem to be removed for repair.

The valve 20 is held normally closed or seated by means of a spring 23 which yields under the depression of the lever 16 to permit the valve 20 to open and water to flow through the pipe 3 into the bowl 1. The stem 19 passes up through the opening 13 in the bottom wall 12 of the casing 11 so that when the casing together with the platform 80 6 is lifted out of its seat in the floor 4, the valve stem 19 will not interfere therewith.

The platform 6 is provided with a downwardly extending boss or knob 24 which bears against the lever 16 for depressing the latter for the purpose stated. The platform 6 is 85 yieldingly supported at the proper elevation by means of springs 25 contained in spring cups 26 supported by the floor of the casing 11 to which they are secured. The downward movement of the platform 6 is limited by means of stops 27 on the under side of 90 said platform which come in contact with other stops 28 arranged centrally of the cups 26.

95 From the foregoing description it will be seen that all of the mechanism is located under the floor and is directly accessible by lifting the casing 11 together with the platform 6 from the opening in the floor. The platform 6 may be removed from the casing to give access to the lever 16 and other parts 100 therein and when the casing 11 is removed from the opening in the floor, ready access 105 is given to the cut off valve. This enables the entire operating mechanism of the device to be conveniently adjusted from time to time as may be found necessary. The 110 whole apparatus is entirely automatic in operation, being thrown into action by the

weight of a person standing on the platform and being thrown out of operation by the removal of such weight from the platform.

What I claim is:—

- 5 In flushing apparatus, the combination of an elevated bowl, a water supply pipe leading to said bowl, a depressible foot platform set into the floor adjacent to said bowl, a casing in which said platform is movable detachably seated in an opening in the floor, said casing having its bottom closed with the exception of an opening for a valve stem, an automatic cut off valve in said water sup-
- 10

ply pipe and under said casing, said valve having a stem extending upwardly into said platform casing, a valve opening lever fulcrumed in, attached to and removable with said casing and normally resting on said valve stem, and means for yieldingly upholding said platform.

In testimony whereof I affix my signature in presence of two witnesses.

JOHN S. TAYLOR.
